UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

METHOD AND APPARATUS FOR PRODUCING ELASTIC STRIP MATERIAL.

Application filed March 14, 1924. Serial No. 699,231.

This invention relates to the art of applying to elastic strip material a covering or an associated structure adapted to limit the elongation or the contraction of the strip, as in 5 braiding a cover, for example, onto a strand or a plurality of associated strands of rubber. The particular embodiment of my invention which is shown in the accompanying drawings and described herein is especially 10 adapted for braiding a covering of threads onto a rubber core structure while the latter is in a stretched, attenuated condition, so that the braided covering will limit the contraction of the resulting structure when the 15 same is released from all tensioning means other than the covering itself.

A structure of this character is of especial value, for example, as a cushion element or shock-absorber for the landing gear of an 20 aeroplane, wherein it may be used to provide a cushioning element of appropriate elastic resistance without requiring such weight of rubber as would be necessary to provide the same yielding force if the rubber were free 25 to elongate and contract throughout its natural range. The braided covering is also adapted to limit the elongation and contraction of the strip to a certain, definite range.

Heretofore, so far as I am aware, in producing such structure by feeding a rubber core under tension through a braiding machine or the like, the core has been progressively tensioned by means of a friction brake mechanism, as by braking a stock reel from 30 which the core is drawn through the braider, with the result of lack of uniformity in the characteristics of the product due to the variable and indeterminate action of the brake or of the reel in giving off the core material.

40 My chief object is to provide an improved elastic cord structure or the like, of the character described, which will be uniform in its characteristics throughout its length, requiring the same determinate force to 45 elongate it to a given extent, and to provide improved, economical and accurate procedure and apparatus for producing the same, and especially for producing it as a continuous strip. Another object is to provide 50 apparatus readily adaptable for producing such structures of different cross-sectional sizes and of different ranges of stretchability.

Of the accompanying drawings,

55 Fig. 1 is a front elevation of apparatus embodying and adapted to carry out my in-

vention in its preferred form, and the work therein.

Fig. 2 is a front elevation of parts of the same, on a larger scale, parts being broken away and in section.

60 Fig. 3 is a side elevation of the apparatus as viewed from the right of Fig. 1.

Fig. 4 is a horizontal section on line 4—4 of Fig. 2.

Fig. 5 is a perspective, fragmentary view 65 of the product, part of the cover being removed for the purpose of illustration.

General description.

Referring to the drawings, and first more 70 particularly to Fig. 1, the apparatus comprises two braiders, A and B, which may be of known design, for braiding respectively an inner and an outer sheath of threads upon the rubber core structure, a large feeder pulley C at the upper part of the machine for pulling the work upward through said braiders, a retarding device D adapted to effect 75 a stretching of the core material as the latter passes to said braiders, change-speed gearing E for varying the relative speeds of said feeding pulley and the rollers of said retarding device, and a frictionally driven 80 reeling device F for the finished work, the apparatus being adapted continuously to draw a plurality of elastic rubber strands or threads 10, 10, from a source of supply into close, parallel association with each other to provide an elastic core structure 10*, progressively and uniformly to tension said core 85 structure, to braid an inner cover or sheath 11 and a similar outer cover 12 upon said core structure, and to reel up the finished 90 product, designated 13.

95 Braider drive mechanism.

The braiding mechanism, of the usual double-deck type for braiding two covers or sheaths upon strip material, comprises 100 a pair of side-frames 14, 14, upon which are mounted the several parts of the braiding mechanism, including the feeder pulley C, said frames being mounted upon a table 15. The driving mechanism comprises a motor 16 (Fig. 1), here shown as secured 105 to an overhead support, said motor having belt connection to a countershaft 17, and the latter having belt connection to a pulley 20 mounted on a stub shaft 21 projecting from one of the frame members 14. Said pulley 110

20 is provided on its rear face with a bevel gear 22 adapted to drive the braiders in a well known manner, the driving mechanism of the two braiders being connected by a vertical, drive-shaft 27.

Feeder pulley.

The upper end of the shaft 27 is provided with a worm 28, meshed with a worm gear 35 secured to one end of a shaft 36, journaled in the respective side frames 14, (see especially Fig. 3), the other end of said shaft being provided with a gear 37 which is meshed with a gear 38 secured to the adjacent end 15 of a parallel shaft 39, the latter being journaled in suitable brackets mounted on the respective frame members 14. A pinion 40 loosely journaled on said shaft 39 near its middle is meshed with a gear 41 formed on 20 the periphery of the feeder pulley 42, said feeder pulley being secured on a shaft 43 journaled in the tops of the frame members 14. The feeder pulley 42 is formed on its periphery with laterally tapered groove face 25 adapted to receive the finished work 13 in a plurality of spiral turns, so that the pulley has sufficient frictional contact with the work to pull the latter through the machine under substantial tension, and to permit the elastic 30 work to slip laterally toward a flange at the small end of the said face, while it grips the pulley against circumferential slippage, so as to maintain alignment of the work as it passes from the braiders to the feeder 35 pulley notwithstanding the spiral disposition of the work on the pulley.

The pinion 40 has its hub formed with clutch teeth adapted normally to be engaged by a supplemental clutch member 44 slidably keyed upon its shaft 39, said clutch being provided with a shipper-lever 45 pivoted on a collar 46 loosely mounted upon the shaft 43, between spacing collars 47, 47, secured on said shaft. The flexible free end 45 of said shipper lever overlies a hereinafter described bracket 80, secured to the frame members 14, and said lever is provided with a stud 45^a, adapted to be inserted in one or the other of a pair of apertures 80^a, 80^b, 50 in said bracket, to hold the clutch engaged or disengaged. The front end of the shaft 39 is provided with a pulley 48 having driving connection, through drive-belt 49, with a counter-shaft 50 journaled in overhead brackets (see Fig. 1), for driving the reeling device F.

For manually driving the feeder-pulley 42 on occasion, as when threading the work through the machine in preparing for operation, with the clutch 44 disengaged, a shaft 51 has secured thereon a pinion 52 meshed with the gear 41 of the feeder pulley, said shaft 51 being journaled in the legs of a U-shaped bracket 53, shown most clearly in 65 Fig. 2, extending from the frame members

14, one end of said shaft being provided with a hand-wheel 54, and its other end being provided with a ratchet 55 engaged by a stop-pawl 56 pivoted on the bracket 53, to prevent unintended recession of the feeder pulley 70 42 under the tension of the work. A pair of parallel guide fingers 57, 57 mounted on the bracket 53, are adapted to guide the finished work 13 as it passes from the feeder pulley 42 to the reeling device F. 75

Core tensioning device.

The core tensioning device comprises an upper set of elongated rollers 58, 58, journaled on a bracket 60 secured under the table 80 15, and a lower set of rollers 59, 59, journaled upon a similar bracket 61, the rollers of each set being positioned in staggered relation to those of the other set, to provide maximum contact of the rollers with the 85 rubber strands 10 adapted to constitute the core, said strands being threaded about rollers of the two sets alternately. Secured to the hubs of the rollers 58, 59 are sprockets 62, 62, 63, 63, respectively, and a sprocket 90 25 chain 163 is mounted upon said sprockets alternately, in parallel with the work, said chain also passing about flanged guide sheaves 64, 65, secured to the table 15, and a slow-speed drive or hold-back sprocket 95 30 hereinafter described, constituting a part of the change-speed gearing E, for compelling the core tensioning rollers 58, 59 to rotate at a determinately slow peripheral speed with 95 relation to that of the feeder pulley C. 100

Interposed operatively between the core tensioning rollers 58, 59 and the braiders is a device for maintaining a substantially constant determinate tensioning force upon the core strands as they pass to the braiders, 105 said device comprising a flanged roller 66 journaled in the free end of a vertically swinging frame 67, the latter being pivoted at 68 to the table 15. A flexible cable or chain 69 has one of its ends secured to the free end of the frame 67, passes around a pulley 70 mounted below said frame, thence around pulleys 71, 72 mounted above said frame, and has its other end provided with a depending set of weights 73, 73, adapted to exert a downward pull upon the roller 66 journaled in said frame, said roller being urged upward against its own gravity and that of the frame 67 and the weights 73 by 110 loops of the strands 10 passing partly around said roller between the tensioning rollers 58, 59 and the braiders, the weights 73 being adapted to be varied in number in accordance with the tension desired in the core of the finished product. The change-speed gearing E, as will hereinafter be described, 115 is adapted for varying the relative speeds of the tensioning rollers 58, 59 and the feed pulley C, whereby the core strands may be fed from a source of supply at a suitable 120 125 130

rate to maintain the frame 67 in substantially horizontal position, so that the loading force of the floating roller 66 will be kept substantially constant.

5 For guiding the strands 10 into close association with each other as they pass to the braiders, the table 15 is formed with a central aperture 74 in which is mounted a guide sleeve 75 for said strands, said sleeve being 10 formed with a circular aperture and a flared conical guide extending downwardly therefrom, so as to guide the strands into a compact bundle.

15 *Change speed gearing.*

The change speed gearing E and the drive therefor comprises a sprocket 76 secured on the shaft 43 above described, said sprocket having driving connection, through a chain 20 77, a sprocket 78, a countershaft 79 mounted on the bracket 80, a sprocket 81, and a chain 82, with a sprocket 83 secured on the main drive-shaft 84 of the change-speed gearing E. A forked gear-shifting lever 85, fulcrumed upon the shaft 84, straddles a gear 86 slidably keyed on said shaft, so that said lever and gear are manually adjustable longitudinally on said shaft. One end of the lever 85 is provided with a handle 87 and a 30 spring-bolt 187 adapted to be engaged selectively in one or another of an inclined series of apertures 88 formed in a locking-plate 89, (see Fig. 3) to hold said lever 85 in suitable angular position for a gear 90, journaled in 35 its forked end and meshed with the gear 86, to be engaged selectively with one or another of a series of graduated gears 91. 91, secured upon an adjacent shaft 92.

Said shaft 92 is provided at its front end 40 with a gear 93 (Fig. 1) meshed with an idler gear 94, the latter being journaled on an adjustable spindle mounted in an arcuate slot 94^a in the front frame of the change speed device, said gear 94 in turn being meshed 45 with a gear 95 on the front end of a counter-shaft 96, upon the rear end of which is secured the sprocket 97, above referred to, for maintaining the relatively slow speed of the tensioning rollers 58, 59. The adjustable 50 feature of the idler gear 94 permits the gear 95 to be of optional size, thus multiplying the number of speed ratios available in the device. The front end of the shaft 92 also is provided with a handwheel 98 for preparatory hand operation or for preserving 55 the tension of the core material while the lever 87 is reset to change the gear ratio.

Core material supply.

60 A reel 99 (Fig. 1) is journaled on a floor bracket 100 adjacent the braiding apparatus and adapted to give off the rubber strands or threads 10 under very little tension, said strands preferably being initially dusted 65 with a suitable lubricant such as soapstone,

and wound preferably with uniform but little tension, upon said reel, the respective ends of said strands being grouped together and tied, and each end provided with an elastic "leader", the leader at the forward 70 end of the set of strands facilitating the starting of the work through the braiding machine and permitting the leading end portion of the core to be braided while under suitable tension, and the "leader" at the 75 rear end of the set of strands serving the same purpose with relation to the trailing end portion of the core.

The hub of the reel 99 is provided with a 80 brake-drum 101, engaged by a lightly weighted brake-band 102, for insuring the uniform withdrawal of the work without subjecting the latter to very much tension.

85 *Take-up reel.*

For winding up the finished work, 13, a reel 103 (Fig. 1) is journaled on a pair of floor brackets 104, said reel being secured upon a common shaft with a gear 105, the latter being meshed with a drive pinion 106 90 secured on a projecting shaft 107, the latter being journaled in a pair of floor brackets such as 108 (Fig. 1) at one side of the brackets 104. The shaft 107 is adapted to be frictionally driven by a pulley 109, suitable 95 frictional connection being operatively interposed between said shaft and said pulley, the latter being connected by a driving belt 110 with a pulley 111 on the counter shaft 50 hereinbefore described.

100 For guiding the work evenly onto the reel 103, a guide-sheave 112 is journaled on an arm 113, the latter being mounted on a return screw shaft 114, and slidably secured against rotation, for moving the guide-sheave back and forth axially of the reels 103. For driving the shaft 114, said shaft is provided with a ratchet 115 secured thereon and adapted to be driven by a pawl 116 mounted on a pawl arm 216 pivoted on the 110 shaft 114 and adapted to be oscillated by a pitman 117 connecting said pawl arm with an eccentric 118 on the shaft 107.

115 *Operation.*

In the operation of the apparatus, the work being mounted in the machine and started and all parts of the apparatus being driven by the interconnected driving means described, the elastic strands 10 are continuously withdrawn from the reel 99, progressively stretched by a determinate percentage or tensioned with a determinate force, as desired, a two-ply cover is braided upon the tensioned core, and the resulting structure 120 is wound onto the reel 103, all of these operations being performed by the machine automatically, except that the relative speeds of the feed pulley and the tensioning rollers, or the force of the weights 73, is varied from 125 130

time to time by the operator to maintain the desired correlation. For producing a strip having a core stretched to a uniform tension throughout, the preferred practice is to use such weights as to provide a given tension upon the core, and then vary the speed of the hold back means as may be necessary to prevent the floating roller 66 from excessively rising or falling.

- 10 When the rollers 58, 59 are all adapted to be driven at the same surface speed, as shown, there may be a slippage of the core strands on those of the rollers which are nearest to the floating roller 66, depending upon the loading of the latter. I do not find this objectionable but my invention is not wholly limited to driving said rollers at the same surface speed. The arrangement of said rollers is such that, by guiding the strands in a sinuous path and thereby maintaining an extensive frictional contact therewith, slippage of the strands on the rollers nearest the supply reel at least is prevented, so that the strands may be fed from the reel 25 at a determinate speed and with such little tension therein as to make the linear rate of feed a dependable measure for so supplying the strands as to give them a determinate tension in the finished product. As this arrangement of the hold-back rollers is adapted to provide a determinate rate of feed of the substantially untensioned rubber, a substantially uniform percentage of stretch may thereby be obtained, and I do not 30 wholly limit my claims to the loading of the strands as they pass to the braiders.

Modifications may be resorted to without departing from the scope of my invention, which is not limited, for example, to the 40 round-sectioned product here shown, and I do not wholly limit my claims to the specific construction shown or the exact procedure described.

I claim:

- 45 1. Apparatus of the character described comprising means for progressively fabricating a flexible, extensible fibrous structure in association with strip rubber, means for supporting a supply of the strip rubber, means for pulling the product continuously from the 50 fabricating means, hold-back means other than the supply-supporting means for retarding the movement of the rubber to the fabricating means, and means for compelling 55 the withdrawing means and the hold-back means to function with a constant, determinate ratio of feeding speed.

2. Apparatus of the character described comprising means for fabricating a flexible, 60 extensible fibrous structure in association with strip rubber, means for pulling the product continuously from the fabricating means, hold-back means for retarding the movement of the rubber to the fabricating 65 means, means for compelling the pulling

means and the hold-back means to function with a determinate ratio of feeding speeds, and floating-roller tensioning means positioned operatively between the hold-back means and the fabricating means and adapted to exert a uniform, constant tensioning force upon the strip rubber without substantial variation of the mechanical advantage of said force.

3. Apparatus for producing elastic strip material comprising strip rubber and an extensible, fabricated structure associated therewith, said apparatus comprising means for progressively fabricating said structure in association with said strip rubber, means for continuously pulling the product from said fabricating means, hold-back means adapted to give off said strip rubber to said fabricating means, and drive mechanism operatively connecting said hold-back means and said pulling means.

4. Apparatus for producing elastic strip material comprising strip rubber and an extensible, fabricated structure associated therewith, said apparatus comprising means for progressively fabricating said structure in association with said strip rubber, means for continuously pulling the product from said fabricating means, and hold-back means adapted to give off said strip rubber to said fabricating means, the said hold-back means comprising a series of rollers so relatively positioned as to guide the strip rubber in a sinuous path.

5. Apparatus for producing elastic strip material comprising strip rubber and an extensible fabricated structure associated therewith, said apparatus comprising means for progressively fabricating said structure in association with said strip rubber, means for continuously pulling the product from said fabricating means, hold-back means adapted to give off said strip rubber to said fabricating means, and means for exerting a determinate, uniform tension upon said strip rubber as it passes from said hold-back means to said fabricating means, said hold-back means comprising a series of rollers so relatively positioned as to guide said strip rubber in a sinuous path.

6. Apparatus for producing elastic strip material comprising strip rubber and an extensible, fabricated structure associated therewith, said apparatus comprising means for progressively fabricating said structure in association with said strip rubber, means for continuously pulling said strip rubber from said fabricating means, hold-back means adapted to give off said strip rubber to said fabricating means, means for exerting a determinate, uniform tension upon said strip rubber as it passes from said hold-back means to said fabricating means, said hold-back means comprising a series of rollers so relatively positioned as to guide said strip

- rubber in a sinuous path, and said tension means comprising a floating roller adapted to ride in a loop of said strip rubber, and weighting means for said floating roller.
- 5 7. Apparatus for producing elastic strip material comprising strip rubber and an extensible, fabricated structure associated therewith, said apparatus comprising means for progressively fabricating said structure in association with said strip rubber, means for continuously pulling said strip rubber from said fabricating means, hold-back means adapted to give off said strip rubber to said fabricating means, a floating roller 10 adapted to ride in a loop of said strip rubber between said hold-back means and said fabricating means, and drive mechanism operatively connecting said hold-back means and said pulling means.
- 15 8. Apparatus for producing elastic strip material comprising strip rubber and an extensible, fabricated structure associated therewith, said apparatus comprising means for progressively fabricating said structure in association with said strip rubber, means for continuously pulling said strip rubber 15 from said fabricating means, hold-back means adapted to give off said strip rubber to said fabricating means, and drive mechanism operatively connecting said hold-back means and said pulling means, said hold-back means comprising a series of rollers so 20 relatively positioned as to guide said strip rubber in a sinuous path.
- 25 9. Apparatus for producing elastic strip material comprising strip rubber and an extensible, fabricated structure associated therewith, said apparatus comprising means for progressively fabricating said structure in association with said strip rubber, means for continuously pulling said strip rubber 25 from said fabricating means, hold-back means adapted to give off said strip rubber to said fabricating means, and drive mechanism operatively connecting said hold-back means and said pulling means, said floating roller adapted to ride in a loop of said strip rubber between 30 said hold-back means and said fabricating means, and drive mechanism operatively connecting said hold-back means and said pulling means, said drive mechanism being adapted for change of speed ratio and said floating roller being provided with means for determinately varying its force upon the work.
- 35 9. Apparatus for producing elastic strip material comprising strip rubber and an extensible, fabricated structure associated therewith, said apparatus comprising means for progressively fabricating said structure in association with said strip rubber, means for continuously pulling said strip rubber 40 from said fabricating means, hold-back means adapted to give off said strip rubber to said fabricating means, and drive mechanism operatively connecting said hold-back means and said pulling means, said hold-back means comprising a series of rollers so 45 relatively positioned as to guide said strip rubber in a sinuous path.

In witness whereof I have hereunto set my hand this 11th day of March, 1924.

JOHN R. GAMMETER.
